UNITED STATES PATENT OFFICE

RAYMOND D. FOLTZ, OF SOUTH ORANGE, NEW JERSEY, ASSIGNOR TO M. H. DETRICK COMPANY, OF CHICAGO, ILLINOIS, A CORPORATION OF ILLINOIS

FURNACE CONSTRUCTION

Application filed September 3, 1931. Serial No. 560,955.

This invention relates to furnace construction, and pertains particularly to the construction of furnace walls having portions built up of firebrick or refractory tiles arranged to form portions of the heat-resistant closure of the furnace.

The present improvements find particular applicability in furnace constructions, or portions of furnaces, wherein the wall is not subjected to extremely high temperatures, and wherein it is desirable that the wall be particularly effective in preventing transmission of heat through it.

In various types of boiler furnaces, tube stills, and the like, it is desirable to have a large area of heat exchange surface afforded by tubes arranged in rather close association with the encasing or gas-confining wall portions of the furnace, said tubes being connected in the boiler system and being supplied with water or other heat-absorbing fluid, and being also disposed in intimate association with the combustion zone of the furnace. Mercury boilers of recently developed types represent another example of such furnace arrangements.

Due to the close association of these heat-absorbing tubes with the furnace wall portions, the latter are not subjected to excessively high temperatures, and this makes it possible to effect heat savings by effectively insulating the walls externally. In such cases the refractory portion of the wall may be comparatively thin (2½ to 4½ inches) as compared with refractory thicknesses requisite for furnace constructions wherein the wall refractories are subjected to quite high temperatures and rapid slagging.

In order to avail of these possibilities as to thinness of refractories and wall insulation, however, it is necessary that the refractories be safeguarded from other destructive influences to which they are subjected and which are contributive to failures of the type usually referred to as spalling.

A general object of the present invention is the provision of a furnace wall construction particularly adapted to the use of thin refractories and effective heat insulation.

Another object is the provision of such a

wall construction particularly adapted to be assembled in close association with furnace parts such as heat exchange tubes, yet which may be entirely independent thereof structurally, and which can be entirely assembled and disassembled, or repaired or replaced in part, entirely from the outside of the furnace and without interference with or from the associated tubes or boiler parts. 55

Yet another object is the provision of such a wall construction wherein the refractories are effectively safeguarded against influences which are productive of spalling.

A particular object is the provision of an insulated thin refractory wall structure in which the component elements, the refractories particularly, are definitely retained in position, yet susceptible of removal with facility, when desired.

Yet another object is the provision of such a wall structure which may be made tight against air or gas leakage.

Another object is the provision of a wall structure wherein comparatively thin refractories are supported in such fashion as to form a tight wall and are effectively retained in position without being subjected to disadvantageous weight or pressure.

Other and further objects will be pointed out or indicated hereinafter or will be apparent to one skilled in the art upon an understanding of the invention or its employment in use.

For aid in explanation of the invention I show in the accompanying drawings forming a part of this specification certain forms in which the invention may be structurally embodied, but it is to be understood that these are presented merely by way of illustration and are not to be accorded any interpretation calculated to limit the appended claims short of the true and most comprehensive scope of the invention in the art, as I recognize that the invention may be embodied in other forms differing in various particulars from the illustrative embodiments herein illustrated and described.

In the drawings,
Fig. 1 is a detail of furnace wall construc- 100

tion in the nature of a part sectional elevation taken transversely of the wall;

Fig. 2 is in the nature of a part elevational view looking at the inner or furnace chamber side of the wall;

Fig. 3 is a part sectional elevational view of a modified form;

Fig. 4 is a similar part sectional elevational view of a second modified form;

Fig. 5 is a part sectional elevational view of a third modified form;

Fig. 6 is a part sectional elevational view of a fourth modified form; and

Fig. 7 is a part elevational view, looking at the inner or furnace chamber side of a wall constructed as shown in Fig. 5.

Described generally, the invention contemplates a furnace wall structure wherein an external metallic framework is employed to support the refractories which form the heat-resisting wall, as well as the heat-insulating material which may be employed, when desired, as an external covering or lagging for the refractories. The wall refractories are supported on, and in spaced relationship to, this frame by supporting members which are qualified to resist heat and which are adapted to support the refractories individually or independently one above another in the desired association, so as to accommodate their expansion under heating and prevent their falling into the furnace. The arrangement of the frame and supporting members and refractories is such that any of the latter may be removed and replaced from the outside of the furnace and without requiring the dismounting of tubes or the like which may be more or less intimately associated with the inner surfaces of the refractories.

The invention will be most quickly understood in detail from the illustrative embodiments shown in the drawings and now to be described.

In the construction illustrated in Figs. 1 and 2 the reference numeral 10 designates one of a series of metallic frame members in the nature of I-beams or the like, which are disposed upright in collaterally spaced relationship along the outer side of the furnace wall. These function as upright or column members and constitute the principal load-carrying elements of the wall structure. They are suitably secured in the desired spaced and parallel relationship, and serve to support transverse members 11, preferably made of cast iron or similar rigid heat-resistant material, and are secured to the members by suitable bolt connection or the like 12. The transverse members 11 are thus supported on the columns in generally horizontal position and spaced apart one above another. They have upstanding flange portions and transverse flange portions, the former serving as parts for the retentive en-

gagement of the hooks 14 of the tile engaging members 15, and the horizontal flange portions serving as abutments for said tile engaging members. The tile engaging members 15 are in the nature of small brackets 70 of heat-resistant metal, such as cast iron, each having an inwardly extending arm 15^a terminating with an upwardly presented flange or lug 15^b and a downwardly presented flange or lug 15^c. When hooked over the 75 upstanding flange and abutted against the transverse flange of one of the transverse members 11, the tile engaging members are maintained with their arms 15^a in approximately horizontal position and with the terminal flanges 15^b and 15^c spaced a substantial distance from the transverse member. When so supported on the transverse member, the tile engaging members may be slid longitudinally on the latter.

The tiles 16 are made of suitable refractory material, such as fire clay, and are of uniform size and form. Their inner and outer faces preferably are parallel, and their upper and lower edges have the parallel faces 16^a and 16^b which extend obliquely with respect to the inner face. The face 16^a terminates at an upstanding ledge or shoulder portion 16^c, which preferably extends the full width of the tile. The face 16^b terminates at a groove or channel 16^d which preferably extends the full width of the tile and forms an offset or overhanging ledge 16^e at the outer portion of the lower edge of the tile.

The height of the tile and the spacing of 100 the transverse members 11 are such that the vertical distance between the arms 15^a of superjacent tile engaging members will accommodate the tile dimension from the top of the ledge 16^c to the bottom of the ledge 16^e 105 with a clearance. Consequently, a tile may be inserted, between superjacent tile engaging members, lower edge first and from the outer side of the structure, and its ledge 16^e brought to rest upon the lower tile engaging member, 110 and then the upper end of the tile may be rocked inwardly toward the furnace chamber until it comes into abutment with the depending flange or lug 15^c of the upper tile 115 engaging member. Thus the tile is maintained in the position illustrated in Fig. 1, resting on the lower tile engaging member and held by the upper tile engaging member against falling inwardly. The upstanding lug or flange 15^b of the lower tile engaging member seats in the groove which is alongside the ledge 16^c, and maintains the tile against sliding inwardly off of that tile engaging member. The weight of the tile tends to maintain it in the position described. In 120 this position, the upper face of the upper ledge 16^c is spaced some distance below the inwardly extending arm of the upper tile engaging member, thus accommodating thermal expansion of the tile. In instances where 125

the tiles are sufficiently narrow, a single one of the tile engaging members may be employed for the support of each tile, and in cases in which the tiles are wide, two or more of the tile engaging members may be employed for the support of each tile. The vertical spacing of the tile engaging members should be such that a small clearance is allowed between the oblique faces of super-jacent tiles, and this space is filled with a suitable refractory material which is effective to seal the joint. Fire clay may be used for this purpose, same being applied to the oblique faces of the tiles as they are placed in the structure.

For the purpose of further sealing the wall, it may be desirable to apply to the outer faces of the tiles, after they have been assembled in the structure, a thin coating of plastic heat insulating or refractory material, as indicated at 17. Then, outside of this may be applied a layer of insulating material 18, of the desired thickness. The application of these exterior coverings may be made quite effectively, as each tile is definitely held against displacement into the furnace chamber, and hence can sustain the pressure necessary for the application of the external sheathing material which may be either of plastic nature or otherwise.

In the modified form of construction illustrated in Fig. 3, the parts correspond in general to those of the first form described, but with the exception that the tile engaging members do not have a depending flange for engagement with the upper portion of the subjacent tile. In this form the upper ledge of the lower tile abuts a rearward face of the superjacent tile, and thus the lower tile is held against swinging into the furnace chamber.

In the modified form illustrated in Fig. 4, the parts correspond in general to the parts above described, but the tile grooves which receive the tile engaging members are spaced somewhat above their lower ends.

In the modified construction illustrated in Fig. 5, the transverse members 11' are spaced away from the columns 10 by means of spacing members 19, so that their lower flanges are in a position where they function as the supports for the tiles. To retain the tiles from sliding inwardly off of the flanges, the latter are provided with upstanding marginal portions 11^a adapted to seat in the undercut lower marginal groove of the tiles. The tile engaging members 20 have upstanding flange portions 20^a and 20^b adapted to engage opposite faces of the transverse members 11', and depending lugs or flanges 20^c adapted to engage in the upper marginal groove of the subjacent tile and retain the tile against toppling outwardly or inwardly. The tile engaging members 20 are slideable along the transverse members 11', and

after the subjacent tile has been placed in proper position, the engaging member or members 20 therefor are applied to the transverse member 11' to one side of the tile, and then slid laterally into the top groove of the tile, thus establishing the holding connection between the transverse member and the upper end of the tile. The engaging member 20 thus rests on the top of the tile, and accommodates vertical expansion of the tile by virtue of the fact that it can slide upwardly on the transverse member 11'. When it is desired to remove the tile, the engaging member 20 is slid laterally into the groove of the adjacent tile, which thus frees the upper end of the first mentioned tile and permits it to be withdrawn.

In the construction illustrated in Fig. 6, the transverse members 11'' are likewise spaced from the column members 10 by spacers 19', and their inwardly presented flanges form supporting rests for the lower margins of the tiles, but they are not provided with the upstanding marginal ledges. The retaining members 20', however, have their flanges 20^a of sufficient height to extend above the horizontal flange of the transverse member and to form a retaining lug to seat in the lower groove of the tile and thus retain the lower edge of the tile against sliding inwardly off of the transverse member. In other particulars the construction corresponds to that illustrated in Fig. 5. In either instance the meeting top and bottom faces of the tiles may be oblique to the inner tile faces, as shown in Fig. 6, or perpendicular thereto, as shown in Fig. 5. In the various modified forms illustrated in Figs. 3 to 7 inclusive, the column members 10 and sheathing portions 17 and 18 may correspond to similar parts as above described with reference to the embodiment shown in Fig. 1.

It will be ascertained from the foregoing that the present invention affords a construction wherein an effectively tight refractory wall may be provided and the respective refractories definitely retained in the desired relationship in the structure without being dependent upon one another for support. It will also be observed that the construction provides for the accommodation of the thermal expansion of the refractories in such fashion that injurious stresses, such as may contribute to spalling, are not imposed upon them. While the structure is exceedingly stable, even when quite thin refractories are used, it nevertheless permits the removal and replacement of any of the refractories entirely from the outside of the structure and without involving the dismantling of any portions of the structure other than those which it is desired to remove.

What I claim is:

1. A furnace wall structure comprising, in combination, upright frame members spaced

apart from one another in a row, transverse members carried by said upright members and spaced apart one above another, refractory tiles supported by said transverse members one above another and spaced apart from said upright members to form a furnace wall lining, said tiles having ledges at the outer portions of their upper and lower edges, and tile engaging members shiftably anchored on said transverse members and engaging the tile ledges to retain the tiles against displacement inwardly of the furnace chamber, the spacing of said transverse members affording room between them permitting removal and insertion of the tiles from the outer side of the structure.

2. A furnace wall structure comprising, in combination, upright frame members arranged in collaterally spaced relationship, transverse members carried by said upright members to one side thereof and spaced apart one above another, tile engaging members anchored on said transverse members and extending therefrom toward the inner side of the wall, said tile engaging members having lugs at their inner ends, refractory tiles supported by the transverse members one above another to form a furnace wall lining spaced from the upright frame members, said tiles having grooves at their lower margins and said lugs being engaged with said grooves to retain the lower portions of the tiles against displacement inwardly from the wall, said tiles having ledges on their upper margins for engagement with adjacent parts to retain the upper portions of the tiles against displacement inwardly from the wall, the spacing of said frame members and transverse members and the size of said tiles being such as to permit movement of the latter to and from assembled position between the transverse members.

3. A furnace wall structure comprising, in combination, upright frame members spaced apart collaterally, transverse members carried by said frame members to one side thereof, refractory tiles supported by the transverse members one above another to form a furnace wall lining spaced from the upright members, said tiles having ledges at their upper and lower margins, and tile-retaining members movably anchored on the transverse members at spaced intervals longitudinally thereof, said tile-retaining members extending between superimposed tiles and engaging the ledges thereof to retain the tiles against displacement inwardly from the wall, the spacing of said transverse members and the size of said tiles being such as to permit insertion and withdrawal of the latter entirely from the outside of the wall structure.

4. Furnace wall structure comprising, in combination, upright frame members spaced apart collaterally, transverse members connected to adjacent upright members and

spaced apart one above another, tile engaging members anchored on said transverse members and spaced apart from one another longitudinally thereof and extending therefrom toward the inner side of the wall, said tile engaging members having offset portions at their inner ends, and refractory tiles supported on said tile engaging members one above another and spaced apart from said frame members to form a refractory wall lining, said tiles having ledges at their lower margins engaging said offset portions of the tile engaging members to retain the tiles against displacement inwardly from the wall, the spacing of said transverse members being such as to permit withdrawal of the tiles outwardly from the wall.

5. A wall structure as specified in claim 4 and wherein said tile engaging members are shiftable longitudinally of the transverse members into and out of engagement with the tile ledges.

6. Furnace wall structure comprising, in combination, upright frame members, transverse members connected to adjacent upright members at one side thereof and disposed one above another, refractory tiles arranged one above another and supported by the transverse members to form a refractory wall lining spaced from the upright members, said tiles having grooves in their upper and lower margins, and tile engaging members anchored on the transverse members and shiftable longitudinally thereof and engaged in said grooves to retain the tiles against displacement inwardly from the wall, said tile engaging members being disengageable from the tile grooves by movement longitudinally of the transverse members and the tiles thereupon being movable outwardly from the wall between the latter.

7. Furnace wall structure comprising, in combination, upright frame members, transverse members connected to adjacent upright members and disposed one above another at one side thereof, said transverse members having ledges extending toward the inner side of the wall, refractory tiles supported on said ledges one above another to form a furnace wall lining spaced from the upright members, and tile engaging members anchored on said transverse members and shiftable longitudinally thereof, said tile engaging members having engagement with marginal portions of the tiles to retain them against displacement inwardly from the wall.

8. Furnace wall structure comprising, in combination, upright frame members spaced apart collaterally, transverse members connected to adjacent upright members at one side of the latter and spaced apart one above another, refractory tiles arranged in courses one above another to form a furnace wall lining spaced apart from the upright frame members, respective courses of said tiles be-

ing carried by respective transverse members, tile engaging members anchored on the transverse members and extending between the courses and engaging the tiles to retain them against displacement inwardly from the wall, and heat-insulating material arranged as an external sheathing for the tiles between them and the upright frame members.

9. Furnace wall structure comprising, in combination, upright frame members arranged in collaterally spaced relationship, transverse members connected to adjacent upright members and disposed one above another, tile engaging members anchored on said transverse members and extending therefrom toward the inner side of the wall, refractory tiles supported on said tile engaging members one above another to form a refractory wall lining spaced apart from said upright members and said transverse members, said tile engaging members terminating short of the inner side of said lining and having engagement with the tiles to retain them against displacement inwardly from the wall, and heat-insulating material applied to the outer faces of said tiles to form a sheathing between them and said upright and transverse members.

In testimony whereof I have hereunto subscribed my name.

RAYMOND D. FOLTZ.
